Josef Schlagenhaufner,
by *Wendell S. Lunt*
His Attorney.

UNITED STATES PATENT OFFICE.

JOSEF SCHLAGENHAUFER, OF MUNICH, GERMANY, ASSIGNOR, BY MESNE ASSIGNMENTS, TO GENERAL ELECTRIC COMPANY, A CORPORATION OF NEW YORK.

ELECTRIC SWITCH.

Application filed October 4, 1923, Serial No. 666,548, and in Germany November 25, 1922.

My invention relates to switch mechanism, and more particularly to motor starting switches of the type which are arranged to establish one set of connections for starting 5 the motor and another set of connections for normal running operation of the motor, such as the star-delta switch or the like. In switches of this type it is desirable that the switching operations be effected positively 10 and quickly in a definite order and if this order of movement is in any way confused the protective fuses in the motor circuit may be burned out, or worse still, damage may be done to the motor windings or coils.

15 The object of my present invention is to produce a switch mechanism whereby these defects are avoided and which moreover is so constructed that the circuit is broken and closed instantaneously.

20 In the accompanying drawings in which I have shown by way of example an embodiment of my invention in a manually operated star-delta motor starting switch having an off, a starting and a running position, Fig. 1 is a 25 sectional elevation of such a switch constructed in accordance with my invention, Figs. 2 and 3 show the locking mechanism for the manual operating lever or handle of the switch in two different positions, Figs. 4, 5, 6 30 show the relation of the several parts of the switch operating mechanism with various positions of the manual operating switch lever, Fig. 7 is a diagram of the electric circuit of the motor starting switch, and Fig. 35 8 is a section along A—B in Fig. 1, shown in the direction of the arrow C in said figure.

On the usual contact operating shaft 1 of the starting switch illustrated in Fig. 1 is mounted for independent rotation the manual 40 operating switch handle or lever 2, the lower end of which as shown in Fig. 4 is formed in the shape of two cam surfaces provided with different curves. In the path of these curves are the thrust locking pins 3 and 4, 45 guided by pivots which are mounted to slide under the action of biasing springs 5 and 6 so that the pins 3 and 4 tend to enter notches *e*, *f*, *g*, provided in a cooperating locking disc formed integral with the disc lever 9 which is 50 suitably secured to the switch shaft 1. The locking pins 3 and 4 have suitable extensions which are arranged to slide upon the cam shaped curves of the lower end of the switch lever 2 so that the operation of the pins 3 and 55 4 into the notches *e*, *f*, *g*, of the cooperating

locking disc on the disc lever 9 is controlled by the position of the cam portion of the switch lever 2.

The manual operating lever 2 is operable between an off, a starting and a running position and is arranged to operate the disc lever 9, and hence the contact members 11, through the agency of a flexible spring 7. Preferably the spring 7 is disposed around the switch shaft 1 with the ends thereof extending on opposite sides of the pins 8 and 10, carried respectively by the manual operating lever 2 and the disc lever 9. The arrangement is such that if the switch lever 2 is turned from the off position in which it is shown in Fig. 4 60 to the left, the limb *i* of the spring 7 is carried along by the pin 8, whereas the other limb *k* of the said spring will bear against the pin 10 provided on the disc lever 9. Consequently, a tension will be produced in the 65 spring 7 which tends to move the disc lever 9 in the same direction as the switch lever 2 is moved. The tension is maintained in the spring 7 due to the fact that the pin 3 engages with the notch *e* which is provided in 70 the disc portion of the lever 9, and thus prevents movement of the latter. Upon further rotation of the switch lever 2, the pin 3 will be lifted out of the notch *e* by the cam surface 1 so that the disc lever 9 is released. This 75 permits the lever 9, together with the switch shaft 1 and the switch blades 11 to be whirled around by the spring 7 until the locking pin 4 enters the notch *g* shown in Fig. 5. It will be understood that after the portion *m* of the 80 cam surface passes the locking pin 4, the latter will be free to engage with the cooperating 85 disc portion of lever 9, while the pin 3 is maintained out of locking relation with the notch *g* by the cam surface 1. When the 90 switch lever 2 is now rotated to the right to the position in which it is shown in Fig. 6, the 95 following occurs:

As the switch operating lever 2 is turned back over an arc of 180° the pins 3 and 4 remain in their respective positions as shown in Fig. 5 until after the pin 3 passes over the inclined portion of the cam surface 1 and enters the notch *g*. Due to the pivotal mounting of locking pin 4, a slight pivotal movement thereof occurs when the switch lever 2 is operated to the right. This permits the pin 3 to enter notch *g* before, a little later, pin 4 is lifted out of the notch *g* by the ascending portion *m* of the cam surface above referred 100 105 110

to. As the manual operating lever 2 is moved to the right it will be evident that the limb *k* of the spring 7 will be carried along by the pin 8 while the limb *i* of the spring will 5 engage with and bias the disc lever 9 to follow the movement of the manual operating lever 2. The disc lever 9, however, is held in the position shown in Fig. 5 first by the pin 4 engaging the notch *g* and then by the pin 3 10 engaging the notch *g* until the latter is withdrawn from the notch *g* by the projection *n*. This releases the disc lever 9 secured to the shaft 1 which, together with the switch blades 11, is rapidly whirled around until the 15 locking pins 3 and 4 both enter the notch *f* on the switch operating lever 9 as shown in Fig. 6.

When the manual switch lever 2 is moved back to its initial position as shown in Fig. 4, 20 pins 3 and 4 are lifted out of the notch *f* upon respectively engaging with the projection *n* and the ascending portion *p* of the cam surface. The pin 3 then quickly drops back to 25 reengage the notch *e* and arrest the switch operating lever 9 when it reaches the position shown in Fig. 4.

It will be observed that the action of the spring 7 is uniform in both directions and serves to quickly and positively rotate the 30 switch shaft 1 and the switch blades 11 between the circuit-closing and the circuit-opening positions.

Fig. 7 shows schematically the usual circuit connections of a star-delta motor starting 35 switch which may be employed with my improved form of switch illustrated in Fig. 1. Fig. 8 shows the relative positions of the several operating parts of my improved switch mechanism at the moment when the pin 3 is 40 lifted out of the notch *e* and the pin 4 is lowered toward the cam surface. This figure also shows the action of the spring 7.

In order to insure the proper sequence of 45 operation and to maintain the manual switch operating lever 2 in its respective off, starting and running positions, the switch mechanism may be provided with a locking mechanism constructed as shown in Figs. 2 and 3. The locking mechanism comprises a locking dog 50 12 which is pivotally mounted upon the switch lever 2 and is biased by means of suitable springs as indicated in the drawing to a central position. The locking dog 12 is arranged to cooperate with notches formed in 55 the partition 14 which separates the switch operating mechanism from the switch contact mechanism as shown in Fig. 1. A notch of the form shown in Fig. 2 is provided in the partition 14 for maintaining the manual operating switch lever 2 in the central or off position. It will be observed that in this 60 position of the arm 12, movement of the lever 2 towards the right is impossible and only a switch movement toward the left can be effected. In both the starting and the running

positions of the switch lever 2, the notch in the partition 14 is so shaped that the locking dog 12 can swing freely to one or the other side as shown more in detail in Fig. 3. This locking mechanism insures that the switch lever 2 is operated first to the starting and then to the running position and at the same time permits the switch lever to be returned to the central or off position. The locking mechanism operates in the following manner: 70 When the manual operating lever 2 is moved from the central or off position to the left it will be evident that the locking dog 12 yields to the right and slides along the partition 14 until it engages the notch in the partition at 75 the starting position as shown in Fig. 3. Upon the engagement of the locking dog 12 with the right hand sloping side of the notch the return of the switch lever 2 to the central or off position is prevented. However, upon 80 a slight further movement of the lever 2 to the left, the locking dog 12 is permitted to rotate to its central or biased position and a return movement of the switch lever 2 to the right serves to depress the locking dog 12 to the 85 left, in which position it easily passes the central or off position notch shown in Fig. 2 and slides along the face of partition 14 until the 90 left hand sloping edge of the notch located in the partition at the running position is encountered. The switch lever 2 is maintained in the running position by engagement of the dog 12 with the left hand sloping edge of the 95 notch in a manner similar to that previously described. A still further movement of the 100 switch lever 2 to the right again permits the locking dog 12 to move to its central or biased position, thereby permitting return movement of the switch lever 2 to its off position in which the locking dog 12 reengages the notch 105 in partition 14, as shown in Fig. 2.

I claim as my invention:

1. In a motor starting switch, the combination with contact members, of a switch lever operable in each direction from a plurality of positions, yielding means operatively connecting said switch lever with said contact members, means comprising a stationary part provided with notches and a locking arm mounted upon said switch lever and adapted to engage said notches for retaining the switch lever positively in its positions, said locking arm and said notches being arranged to require movement of the switch lever in one direction from each of said positions before permitting movement of the lever in the other direction from said position. 110

2. In a switch mechanism, the combination with a movable contact member having a plurality of positions, of a switch lever movable between a plurality of corresponding positions, a yielding connection between said contact member and said lever, and means comprising a locking member and a plurality of 120 125 130

- locking pins controlled by said switch lever to successively engage with said locking member for holding the said contact member in one position while the said switch lever is operated from one position through an intermediate position to another position, each of said locking pins operating separately to hold the contact member in the said one position during a different portion of the movement of said switch lever.
3. In a switch mechanism, the combination with a movable contact member having a plurality of positions, of a switch lever movable between a plurality of corresponding positions, a yielding connection between said contact member and said lever, a notched disc secured to said contact members, and a pair of independently operable locking pins controlled by said switch lever and arranged to successively engage with a notch in said disc for holding the said contact member in one position while the said switch lever is operated from one position through an intermediate position to another position and thereupon release the contact member for quick operation under the action of said yielding connection from said one position through the corresponding intermediate position to the position corresponding to said other position of the switch lever, said locking pins each operating to hold the contact member in said one position during a different portion of the movement of said switch lever.
4. In a motor starting switch, the combination with a movable contact member having an off position intermediate a motor starting and a motor running position, of a switch lever movable from starting through an off to a running position, a yielding connection between said switch lever and said contact member to effect operation of the contact member to a position corresponding to the position of the switch lever, a notched member secured to the said contact member, a pair of independently operable locking pins adapted to engage with a notch in said notched member, and a cam associated with said switch lever and having surfaces arranged to successively engage said pins with a notch in said notched member to hold the contact member in the starting position while the switch lever is operated from the starting through the off position to the running position and thereupon release the contact member for quick operation under the action of said yielding connection from said starting position through the off position to the run-
- ning position, each of said locking pins operating during a different portion of the movement of said switch lever to hold the said contact member in said starting position.
5. In a motor starting switch, the combination with a movable contact member having an off position intermediate a motor starting and a motor running position, of a switch lever movable successively between a corresponding off, a starting and a running position, a yielding connection between said switch lever and said contact member to effect operation of the contact member to a position corresponding to the position of the switch lever, a notched member secured to the contact members, a pair of independently operable locking pins biased into engagement with each of a plurality of notches in said member, and a cam associated with said switch lever and provided with surfaces for separately controlling the operation of said pins into and out of engagement with the notches in said notched member to maintain the contact member in each of its positions until the switch lever is operated to the next successive one of its positions, said locking pins each operating separately to hold the contact member in said starting position during a different portion of the movement of said switch lever between the starting position and the running position.
6. A motor starting switch comprising contact members, a shaft carrying said contact members and operable between an off, starting and a running position, a disc lever secured to said shaft and provided with a notch for each of said positions, a switch lever mounted for operation to an off, a starting and a running position independently of said switch shaft, a spring connection between said switch lever and said disc lever for biasing the said switch shaft to a position corresponding to the position of the switch lever, a pair of independently operable locking pins each biased to engage with the notches in said disc lever; and a cam associated with said switch lever and having separate surfaces for independently controlling the engagement of said pins with said disc lever to insure a quick operation of said switch shaft to and from said off, starting and running positions by said spring upon operation of said switch lever to the corresponding position.

In testimony whereof I affix my signature.

JOSEF SCHLAGENHAUFER.
